UNITED STATES PATENT OFFICE.

ROBERT W. SCOTT, OF BOSTON, MASSACHUSETTS, ASSIGNOR TO SCOTT & WILLIAMS,
INCORPORATED, OF CAMDEN, NEW JERSEY, A CORPORATION OF NEW JERSEY.

KNITTING-MACHINE NEEDLE.

1,097,732.

specification of Letters Patent. Patented May 26, 1914.

Application filed October 1, 1913. Serial No. 792,872.

To all whom it may concern:

Be it known that I, ROBERT W. SCOTT, a citizen of the United States, and resident of Boston, in the county of Suffolk and State 5 of Massachusetts, have invented a certain new and useful Improvement in Knitting-Machine Needles, of which the following is a specification.

An object of my invention is to provide a 10 knitting machine needle capable of operation at a high linear speed without breakage, which needle will place a minimum strain upon the yarn engaging it and will have other advantages.

15 In the accompanying drawings, Figure 1 is a side elevation illustrating one position of the needle latch or presser; Fig. 2 is a longitudinal section through the latch or presser; Fig. 3 is a section on the line 3—3 20 of Fig. 2; Fig. 4 shows typical cross-sections on the line 4—4, Fig. 1; Fig. 5 is a diagram showing the usual relation of the yarn to the parts of the needle.

In the usual construction of latch needles 25 for use in knitting machines the needle comprises a shank, a hook, and a pivoted latch to cover the point of the hook whenever said latch is encountered by a loop of yarn moving toward the head of the needle. One of 30 the chief factors limiting the size of the knit loop which may be made upon one of these needles is the necessary width of the hook, which is short and rigid. The latch for covering the said hook makes an angle with

35 the shank of the needle subtending the gap between the shank and the point of the hook. If the slope of the angle is too sharp, an additional frictional strain upon the yarn loop being cast over the said latch and free 40 end of the hook is occasioned. The latches of the prior art therefore are relatively long, to reduce this angle as much as possible. A frequent cause of breakage of such latches is found in the hammer blow delivered upon 45 the short rigid hook by the rapidly moving latch when the needle is drawn through a loop of the yarn acting to close the latch. This is known to be the limiting factor of the linear speed which may be given the 50 needle.

The comparatively long latches of the prior needles are also open to objection because the necessary freedom of the needle in its groove or of the latch in the slot of the 55 needles permits a multiplied movement of

the end of the latch which is increased as the latch is increased in length so that in the cases of machines having webholders or other instruments standing between the needles, or of rib knitting machines, the 55 swinging latches interfere with the shanks of the needles of the other set, with said instruments, or with the web-holders, and impose a limitation on the gage or distance apart of the needles due to the tendency of a 65 latch, the free movement of which is interfered with, to sever the yarn.

My new needle comprises a shank 1, which may be of the same construction as that of the needles of the prior art. This 70 shank is reduced in cross-section toward its point or end 2, and the reduced portion bent over to form a comparatively long, thin hook or beard 3. The finished needle is given a spring temper to make the beard 3 resilient. 75 In the shank of the needle near the reduced portion 2 I mill a slot 4 completely through the needle, in which slot a short, rigid, swinging latch or presser 5 is pivoted at 6. The length of the latch, the position of the 80 point of the hook or beard when at rest, and the diameter of the yarn may be proportioned substantially as shown in Fig. 5. The point of the open beard is at a position bringing it within the arc swept by the end of the 85 latch. It will be seen that the arc described by the presser is relatively very small in proportion to the arc necessarily swept by needle latches as now known.

In order to support the beard or hook 3 90 against lateral deflection during the stitch forming movement, which lateral deflection may be caused by the uneven stress of the knitting yarn, I preferably form the end of the latch 5 as a channeled part 8, which 95 presents in cross-section on a plane transverse to the latch a U-shaped figure, the open side of the channel pointing toward the needle shank when the latch is closing. The longitudinal section of the latch may be 100 such as to cause the channel to isolate lateral parts 9 of the walls of the latch at the extreme point of said latch.

The short latch is comparatively rigid laterally of the needle and has but slight tendency to be displaced laterally, due either to failure to fit in its slot, or to actual bending of the metal; this enables me to employ the latch as a lateral support for the beard, 105 which is subjected by the yarn drawn 110

through it to lateral strains occurring normally after the closure of the latch, *i. e.* during the stitch drawing movement of the needle.

5 It will be seen that the closure of the latch 5 will determine the bending of the beard toward the milled slot 4 in the shank of the needle; that the formation of the end 8 of the latch will cause the point of 10 said beard to remain in line with the latch 5, and avoid faults due to the slippage of the hook from under the end of the latch during stitch drawing as well as securing the holding of the beard 3 in its proper plane 15 with respect to the shank 1.

The structure made up of the beard 3, the closed presser or latch 5, and the portion 20 of the needle is thinner from back to front than a rigid-hook latch-needle will be 20 for the same diameter of yarn. Breakage of the latch or of the beard 3 will not be induced by the hammer blows of the short latch 5, because of the reduced linear speed of the point of the latch due to its shorter 25 radius, and because the blow is cushioned by the resiliency of the spring beard 3.

The point or bend 7 of my improved needle may be of sufficient area to pass the yarn freely through, so that the moving needle may draw its own loop if desired without

the aid of yarn-sinking or loop-measuring devices. To this end, the cross-section of the metal of the reduced portion of the needle at the neighborhood of the bend 7 may be circular, or half-circular, or lenticular, as shown in Fig. 3, to present a smooth surface to take against the yarn. 25

I am aware of the patent to Cary No. 47,488, dated August 25, 1865, which discloses broadly the combination of a spring 40 hook with the familiar comparatively long latch, which combination I do not herein claim.

What I claim is:—

A spring needle for knitting machines 45 comprising a shank, a reduced portion turned upon itself to form a comparatively long hook having a resilient point or beard, and a short rigid member pivoted to swing in an arc contacting with the point of the beard, said member having a channeled end 50 interlocking with said hook in the plane in which the member swings.

In testimony whereof I have signed my name in the presence of the subscribing witnesses. 55

ROBERT W. SCOTT.
